TUNER FOR HIGH-FREQUENCY TUBES

Frederic A. Jenks, Dedham, Mass., assignor to
The Sperry Corporation, a corporation of Delaware

Application April 3, 1947, Serial No. 739,211

8 Claims. (Cl. 315—6)

1

This invention relates, generally, to tuners for high frequency tubes, and the invention has reference, more particularly, to a novel tuner for high frequency tubes employing cavity resonators such as the klystron tube.

High frequency tubes of the klystron type employ cavity resonators which have to be tuned to the desired operating frequency of the tube. Where the tube contains more than one cavity resonator, it is usually necessary to tune each cavity so that its operating frequency will equal that or be a harmonic of the frequency of the other cavity resonator or resonators thereof.

Heretofore, where tubes employ a plurality of cavity resonators, it has been difficult to provide simple and dependable means for tuning two or more cavities simultaneously while maintaining the desired fixed frequency relationship between these cavities. Thus, in the prior art conductive rod tuners have been introduced into regions of intense electric field or intense magnetic field components of an excited cavity resonator, thereby causing alteration of the equivalent capacitance or of the equivalent inductance of the resonator, but it has been difficult to effect simultaneous equivalent insertion of these rods into a plurality of resonators at one time and in amounts necessary to obtain accurate gang tuning.

Where attempts have been made to insert a common rod through the adjacent walls of a plurality of resonators, difficulty has been encountered in the rod acting as the inner conductor of a concentric line thereby undesirably coupling the resonators together with the result that feedback takes place producing undesired oscillations.

The principal object of the present invention is to provide a novel tuner adapted to gang-tune a plurality of cavity resonators simultaneously, said tuner being so constructed and arranged as to enable exact tracking of the operating frequencies of the several cavities while at the same time preventing undesired feedback between the cavities.

Another object of the present invention is to provide a novel gang-tuner employing a dielectric rod having conducting tuning elements thereon and extending through aligned bores in the walls of cavity resonators, said rod and bores being so proportioned as to act as a wave guide below cut-off, thereby reducing coupling between the resonators to a minimum and hence preventing encountered feedback and undesired oscillations.

It is another object of the present invention to provide a novel tuner having means for com-

10 pensating for temperature changes while at the same time providing an exceedingly sensitive control of the frequency.

Another object of the present invention is to provide a novel tuner which is adapted to operate largely in the magnetic portion of the resonator field or which may operate in that region of the resonator occupied by both magnetic and electric field components, thereby enhancing the tuning range of the tube.

The invention also relates to the novel features of the instrumentalities described herein, whether or not such are used for the stated objects, or in the stated fields or combinations.

Other objects of the invention will become apparent from the following description taken in connection with the accompanying drawings wherein:

Fig. 1 is a longitudinal, part-sectional view of an ultra-high-frequency tube of the klystron type equipped with the novel tuner of this invention;

Fig. 2 is a sectional view taken along lines 2—2 of Fig. 1 looking in the direction of the arrows;

Fig. 3 is an enlarged sectional view of a portion of the structure of Fig. 1; and

Fig. 4 is a sectional fragmentary view of a modified structure.

Referring now to Figs. 1—3 of the drawings, the reference numeral 1 designates an ultra-high-frequency tube of the klystron type, having a focussing emitter assembly 2 adapted to form in conjunction with an accelerating battery (not shown) a stream of electrons passing centrally through a series of cavity resonators, 3, 4 and 5 provided within the casing of the tube. Output and input power connections to the cavity resonators of the tube are provided by use of concentric line terminals 6, 7 and 8. Substantially field free drift spaces 9 and 10 are provided between the resonators 3 and 4 and 4 and 5 so that velocity modulation taking place in the resonators is converted into density modulation in the drift spaces. The resonators 3, 4 and 5 are shown provided with conductive cylindrical walls 11, 12 and 13 preferably of massive metal construction to enable the rapid dissipation of heat.

According to the preferred arrangement, the walls 11, 12 and 13 of the tube casing are provided with axially aligned bores or guides 14, 15 and 16 located eccentrically with respect to the drift spaces 9 and 10 and within which a dielectric rod 17 as of quartz or glass is longitudinally movable. The bores 14, 15 and 16 and the rod 17 are so proportioned as to act as a wave guide below cut-off at the operating frequencies of the

55 low cut-off.

resonators 3, 4 and 5, thereby reducing the coupling between these resonators by way of the bores and dielectric rod to a minimum, and preventing undesired feedback between the resonators.

In order to effect the tuning of the resonators, the dielectric rod 17 is provided with mutually spaced conducting sleeves or slugs 18, 19 and 20. These sleeves may be electro-deposited copper, for example, although any conducting material such as silver may be used. The sleeves 18, 19 and 20 are so positioned on the rod 17 that as this rod is moved they enter the respective cavity resonators simultaneously and progress into these resonators by equal amounts as the rod 17 is moved.

Inasmuch as the rod 17 is a unitary structure, any movement of this rod effects equal movements of the sleeves 18, 19 and 20 resulting in accurate tuning of the resonators and accurate tracking of all the resonator frequencies.

To effect movement of the rod 17, the same is provided with a thin projecting stem 22 as of tungsten which projects into a sleeve 23 and is secured to the sleeve at its outer end portion 24. The sleeve 23 is, in turn, fixed at its inner end to a cylindrical cup-shaped member 25 having an outer flange portion 26 sealed to one end of a bellows 27, the other end of which bellows is sealed to a cylindrical sleeve member 28 forming a part of the high frequency tube housing, said sleeve member 28 surrounding the rod 17.

Thus, the member 25 in conjunction with bellows 27 and sleeve 28 form a sealed joint permitting longitudinal movement of the rod 17 without affecting the vacuum within the tube. A cover member 29 is attached to the sleeve 23 and carries a bushing 30 within which is turnably mounted hollow shaft 31 provided with suitable flanges for preventing longitudinal movement thereof while permitting turning movement of the shaft.

The outer end of the shaft 31 has a knob 32 secured thereon as by the set screws 33. The hollow shaft 31 surrounds the stem 22 and sleeve 23. This shaft has its inner end threaded at 34 for cooperating with a nut 35 fixed within the cup-shaped member 25. Thus, by turning knob 32, shaft 31 is also turned within the bearing 30 and threaded portion 34 cooperating with nut 35 serves to move the cup-shaped member 25 and hence sleeve 23 longitudinally. Since this sleeve is attached to stem 22, the rod 17 also moves. The sleeve 23 is made of a material such as copper having a coefficient of thermal expansion different from that of the stem 22 so that this bimetallic structure automatically compensates for expansion and contraction of the resonator walls due to operating temperature changes, thereby enhancing the accuracy of the tuning and preventing drifting of the tuned frequencies.

In the form of the invention shown in Fig. 4, the tuning mechanism is shown for tuning resonators operating at different frequencies. Thus, the resonator 36 will operate at a fundamental frequency while the output resonator 37 operates at a higher harmonic thereof. The dielectric rod 17' in this instance is reduced at 38 where it projects into the harmonic resonator 37. The conducting sleeve 39 on this portion of the rod is also of reduced diameter. The operation of the apparatus shown in Fig. 4 is similar to that of the previous figures and feedback is prevented in the same manner.

Inasmuch as all the tuning sleeves move si- 75

multaneously and to the same extent, accurate tracking of the frequencies of the resonators takes place where a plurality of resonators is used. Owing to the use of the stem 22 and sleeve 23 of different thermal expansion coefficients, drifting of the resonator frequencies due to temperature changes is largely avoided.

Since many changes could be made in the above construction and many widely different embodiments of this invention could be made without departing from the scope thereof, it is intended that all matter contained in the above description or shown in the accompanying drawings shall be interpreted as illustrative and not in a limiting sense.

What is claimed is:

1. In a high frequency tube structure having a casing providing a plurality of cavity resonators therewithin, each of said resonators adapted to contain an independent oscillating electromagnetic field, tuning means therefor comprising, a dielectric rod slidable within a bore in said casing interconnecting said resonators, said rod and bore being of a diameter less than that sufficient to guide energy at the resonant frequency of said cavity resonators, mutually spaced tuning sleeves carried by said rod, and means for actuating said rod whereby the same is moved to effect movement of said tuning sleeves into and out of the respective resonators to effect the gang tuning by altering the electromagnetic field in each of said resonators.

2. In a high frequency tube structure of the character described in claim 1 wherein said rod actuating means comprises an actuating knob, screw and nut means actuated thereby, and thermal compensating means interconnecting said screw and nut means to said dielectric rod for effecting movement of the latter while compensating for thermal expansion and contraction of the tube casing.

3. A high frequency tube structure comprising a casing, a plurality of cavity resonators contained within said casing, each of said resonators adapted to contain an independent, oscillating electromagnetic field said casing having a bore interconnecting said resonators, and a dielectric rod slidable within said bore, said rod having conducting members thereon for effecting gang tuning by altering the electromagnetic field in each of said resonators.

4. Ultra high frequency apparatus comprising a plurality of hollow cavity resonators, each of said resonators adapted to contain an independent, oscillating electromagnetic field, means for altering the electromagnetic field in each of said resonators, said means comprising a dielectric rod mounted for translational movement within said resonators, and respective conducting members carried by said rod for movement into and out of said resonators.

5. Ultra high frequency apparatus as defined in claim 4, comprising manually operable means for moving said rod, said manually operable means including a bimetallic element for compensating for temperature changes of the resonator.

6. A high frequency tube structure comprising a casing, a plurality of cavity resonators contained within said casing, said resonators operating at differing frequencies and having differing proportions, said casing having a bore interconnecting said resonators, a dielectric rod slidable within said bore for effecting simultaneous

tuning of said resonators, said rod having conducting members thereon for entering the fields of said resonators, the proportions of the conducting members carried by said rod varying in accordance with the relative proportions of the 5 respective resonators.

7. A high frequency tube having a casing formed with a plurality of cavity resonators therein and having a tuning bore interconnecting said cavity resonators, tuning means for said tube comprising, a dielectric rod projecting through said bore into said cavities from without said casing, means sealing the joint externally of said casing between said rod and said bore, and external means connected with said rod for 15 actuating said rod from a point externally of said sealing means.

8. An ultra high frequency tube having a cathode, an anode, a plurality of cavity resonators oriented along a common axis between said cathode and anode, each of said cavity resonators being adapted to contain an independent, oscillating electromagnetic field, a plurality of tuning bores in the walls of said resonators, said tuning

bores being positioned along a common axis, said axis being arranged parallel to the axis of said resonators and spaced therefrom, a dielectric rod slidably mounted within said bores, conducting members supported by said rod, and means for longitudinally displacing said rod.
